HEDDLE FOR WEAVING DEVICES

Paul A. Sperry, New Haven, Conn.

Application June 22, 1949, Serial No. 100,603

3 Claims. (Cl. 139—96)

1

The present invention relates in general to weaving devices and more particularly to an improved heddle for shedding warp threads during the weaving of a fabric.

An object of the invention is to provide a superior heddle for manipulating warp threads.

A further object of the invention is to provide a superior heddle for facilitating threading warp threads through the harness of a loom and for selectively engaging and disengaging the warp threads.

A still further object of the invention is to provide a superior heddle for use either alone or in conjunction with the usual type of loom-heddles for increasing the number of variations of shed structure.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a side elevation of the improved heddle of this invention;

Fig. 2 is a front edge elevation of the heddle shown in Fig. 1;

Fig. 3 is an enlarged fragmentary perspective view of the heddle of Fig. 1, showing details of the warp-thread engaging-means of the heddle;

Fig. 4 is a vertical sectional view on the line 4—4 of Fig. 3;

Fig. 5 is a horizontal sectional view on the line 5—5 of Fig. 3;

Fig. 6 is a front elevation of a harness embodying a plurality of heddles, some of which are indicated as being mounted in a reverse position with respect to other of the heddles and also showing warp threads adjacent each heddle; and

Fig. 7 is a schematic side elevation of a weaving device embodying both the improved heddles of this invention and conventional heddles.

Heddle construction

Referring especially to Figs. 1, 2 and 3, the improved heddle of this invention comprises preferably a thin relatively-stiff substantially-rectangular blade-like strip of material 10 such as, for example, thin sheet metal or its equivalent, provided at its upper and lower ends respectively with longitudinal notches 11 and 12 cut in one edge of the strip 10 and forming thereby relatively-narrow elongated arms 13 and 14. Although the notched construction of the heddle

2

is preferred from the standpoint of reducing the weight thereof, it is within the purview of the invention to form the heddle without the notches in the opposite ends thereof. The relatively-narrow elongated arms 13 and 14 of the metal strip 10 are provided at their outer ends with apertures 15 and 16 respectively, each aperture constituting means for attaching the heddle in a harness or to the heddle-operating means of a 10 Jacquard-type weaving device.

Formed in the body-portion 17 of the heddle 10 adjacent one end thereof, is warp-thread engaging-means indicated generally at 18. As shown especially well in Fig. 3, the warp-thread 15 engaging-means 18 comprises a substantially-rectangular aperture 19 extending longitudinally of the body-portion 17 of the heddle. Projecting upwardly from the lower edge of the aperture in substantially-vertical transversely spaced-parallel relationship, is a pair of prongs 21 and 22, the bases of which are joined integrally to the lower edge of the aperture 19, the one prong 21 being bent outwardly from the plane of the body-portion of the heddle, i. e., from a plane intersecting the longitudinal edges of the heddle, to the left thereof, as shown in Fig. 2, and the second prong 22 being bent outwardly from the plane of the body-portion 17 of the heddle to the right thereof, that is to say, in a direction opposite to that of the prong 21. The prongs 21 and 22 are substantially the same height and the outer sides of the prongs adjacent their bases are joined to the respective oppositely-disposed longitudinal edges of the aperture 19 by concave edges 23 and 24 respectively of relatively-small radius constituting portions of the lower edge of the aperture. A similar concave edge 25 of relatively-greater radius and substantially intermediate the prongs 21 and 22, joins the oppositely-disposed inner sides of each prong 40 adjacent its base, as shown especially well in Fig. 3.

Uses of heddle

As shown in Fig. 6, a plurality of heddles of this invention is adapted to be supported substantially vertically in a conventional harness 26 of a loom with the plane of the body-portion 17 of each heddle substantially parallel to the warp threads of the loom so that the laterally-projecting prongs 50 21 and 22 respectively of each heddle are adapted to lift the individual warp threads. To this end, the individual warps are in position to be hooked over the corresponding laterally-projecting prongs of the heddles instead of being threaded 55 through an eye thereof, as is characteristic of

the conventional type of heddle, each warp lying against the corresponding side of the body-portion 17 of the heddle. For some types of weaves, it may be desirable to invert some of the heddles as indicated in Fig. 6, to depress the warps which may be done without withdrawing the corresponding warps from the harness. It will be clear that by this relatively-simple warp-engaging means, the individual warp threads may be engaged with and disengaged from a corresponding heddle with ease and dispatch. Moreover, the prongs provide a minimum surface area for contact by the warp threads, thereby reducing frictional drag thereon and at the same time permitting the interchange of warp threads of a wide variety of sizes. The individual warp threads are taken off of a warp-beam or creel in a manner well known to those versed in the art, the raising and lowering of the harnesses forming successive sheds for traversing the shuttle 27 therethrough, which, as indicated in Fig. 7, is supported for longitudinal reciprocal movement on an oscillatory loom-batten 28.

A further use of the heddle of this invention is in conjunction with the conventional type of heddle of a loom for increasing the number of variations of shed structure. Thus, as shown in Fig. 7, four harnesses 29, 30, 31 and 32 are provided, each operated by the usual shedding movement 33, three of the harnesses embodying conventional heddles 34, 35 and 36 respectively and the fourth harness 29 having a plurality of the improved heddles 10. Fig. 7 illustrates one function of one of the heddles 10 wherein a warp thread 37, which passes through the eye 38 of the heddle 36 and normally would be on the bottom of the shed due to the lowered position of the heddle 36, has, however, been caught on one of the laterally-projecting prongs of the heddle 10 and held up so as to be on the top of the shed. By properly arranging one or more sets of heddles 10 with respect to one or more conventional heddles, a large variation in shed structure may be obtained on a conventional loom without necessitating any appreciable alteration thereof.

A still further application of the heddles 10 is in conjunction with a Jacquard loom wherein each individual heddle 10 would be operated independently of the others for forming intricate patterns in a woven fabric. Moreover, it will be understood that it is within the purview of the invention to include all other uses of the heddles to which they adapt themselves. In this connection, it should be pointed out that a harness made up of a plurality of heddles 10 such as shown in Fig. 6, has the characteristics of a reed, that is to say, the front edges of the substantially vertically-arranged heddles 10 constitute means for packing the weft threads up into the fell 39 of the woven fabric, and to this end suitable means may be provided for mounting the heddle-bearing harness to accomplish this result.

The improved heddles of this invention will be seen, therefore, to be adapted to many applications in the weaving of a woven fabric and to be characterized by ease of threading warp threads thereon, minimum frictional engagement with the warp threads and capacity for accommodating warp threads of a wide variety of sizes.

The invention may be carried out in other specific ways than those herein set forth without departing from the spirit and essential characteristics of the invention, and the present embodi-

ments are, therefore, to be considered in all respects as illustrative and not restrictive, and all changes coming within the meaning and equivalency range of the appended claims are intended to be embraced therein.

I claim:

1. A heddle for manipulating warp threads of a fabric-weaving device, the said heddle comprising a blade-like strip of material having apertures at opposite ends thereof respectively for fastening the blade-like heddle in a substantially-vertical operating position, and a relatively-wide aperture in said blade-like heddle between the opposite ends thereof; and warp-engaging means comprising a prong joined integrally at its base with the bottom edge of said relatively-wide aperture, the said prong being narrow relative to the width of said aperture and arranged to project outwardly laterally from a plane intersecting the oppositely-disposed longitudinal edges of said blade-like heddle.

2. A heddle for manipulating warp threads of a fabric-weaving device, the said heddle comprising a blade-like strip of metal having apertures at opposite ends thereof respectively for fastening the blade-like heddle in a substantially-vertical operating position, and a relatively-wide aperture in said blade-like heddle between the opposite ends thereof; and warp-engaging means comprising a pair of prongs joined integrally at their respective bases with the bottom edge of said relatively-wide aperture and in longitudinally-spaced relationship along the bottom edge thereof, the said prongs being narrow relative to said aperture and bent outwardly from and on opposite sides respectively of a plane intersecting the oppositely-disposed longitudinal edges of said blade-like heddle.

3. A heddle for manipulating warp threads of a fabric-weaving device, the said heddle comprising a blade-like strip of metal having apertures at opposite ends thereof respectively for fastening the blade-like heddle in a substantially-vertical operating position, and a relatively-wide aperture in said blade-like heddle between the opposite ends thereof; and warp-engaging means comprising a pair of prongs joined integrally at their respective bases with the bottom edge of said intermediate aperture and in longitudinally-spaced relationship along the bottom edge thereof, the portions of the bottom edge of said relatively-wide aperture which blend the longitudinal sides thereof with the longitudinally-spaced prongs comprising concave edges, the said prongs being narrow relative to said aperture and bent outwardly from and on opposite sides respectively of a plane intersecting the oppositely-disposed longitudinal edges of said blade-like heddle.
